Nelson Howard

UNITED STATES PATENT OFFICE

JOHN K. SMITH, OF LAWRENCE, MASSACHUSETTS, ASSIGNOR TO UNITED SHOE MACHINERY CORPORATION, OF PATERSON, NEW JERSEY, A CORPORATION OF NEW JERSEY

SHOE AND ART OF MAKING THE SAME

Application filed April 13, 1926. Serial No. 101,701.

This invention relates to shoes, and to the art of making them, being herein disclosed particularly with reference to the production of shoes having "close" shanks.

6 The term "welt crease" is applied to the angle between the upper and the projecting margin of the outsole or welt, when present, and is commonly employed to designate this angle in shoes which are not welt shoes as 10 well as in respect to welt shoes. In many kinds of shoes it is desirable that this angle or welt crease be closed, that is, that the margin of the sole or welt be brought into close contact with the upper, particularly at the shank portion, to produce what is known as a "close shank". To this end, the margins of the shank portion of the sole of the shoe are usually bent or shaped inwardly, producing a convex curvature of the shank portion and are brought into relatively close relation to the upper by a leveling operation frequently supplemented by a beating operation. However, not only is it oftentimes difficult to obtain initially the desired close relation, but 20 such close relation is not always maintained in the wear of the shoe, and it is an object of this invention to provide for obtaining and maintaining the desired close relation permanently.

30 In view of the foregoing, in one aspect the invention provides a method of producing and maintaining the desired close shank relation which consists in inserting, in a shoe having an insole, an upper and an outsole secured together in any usual and suitable manner, a line of fastenings through the upper and the margins of the insole and the outsole outside the other fastenings referred to, thereby forming the desired close edge. 35 Preferably, the desired close edge is effected by sewing through the upper and the margins of the insole and outsole along one side or along both sides of the shank portion of the shoe. In a welt shoe, as illustrated, the supplemental seam is located outside the inseam and the outsole-attaching seam. Preferably a through-and-through seam such as a lock-stitch seam of fine thread is employed which may be hidden if desired under the usual 40 channel flap of the outsole which conceals the

sole-attaching stitches and by a channel in the insole if desired.

In another aspect the invention provides a shoe having an insole, an upper and an outsole, a line of fastenings securing the upper and the insole together but not entering the outsole, a second line of fastenings securing the outsole to the shoe, and a third line of fastenings located adjacent to edges of contiguous margins of the insole and outsole and holding the insole, outsole and upper together. In the illustrated shoe a welt is secured to an upper by one line of fastenings and is secured to the outsole by another line of fastenings, and the adjacent margins of the welt, upper and outsole are further secured together by a line of fastenings placed outside of and supplemental to the other lines of fastenings. The welt, upper and insole may be 55 secured together by the usual inseam and the 60 welt and outsole by the usual outsole attaching seam, the outsole, welt, upper and insole, as illustrated, being further secured together by a seam of through-and-through stitches placed 65 outside of and supplemental to the inseam and 70 outsole-attaching seam and located at both 75 sides of the shank portion to hold the extreme margins of the insole and outsole and the upper together in close relation.

In the drawing,

Fig. 1 is a perspective view showing the shank portion of a shoe made in accordance with the present invention;

Fig. 2 is a sectional view through the shank portion of a shoe showing the process of 85 manufacture; and

Fig. 3 is a view similar to Fig. 2 taken after the last is removed and the seams which hold the insole, upper, welt and outsole together have been formed.

In Fig. 2 of the drawings is shown a section of a shoe made in accordance with the usual practice in welt shoemaking. An insole 2 is placed upon a last 4. An upper 6 is lasted in the usual manner, the upper 6 and the welt 8 being subsequently secured to a sewing rib 10 formed on the insole by an inseam 11 which, however, does not enter the outsole. A filler 12 and shank stiffener 14 may be employed as usual and an outsole 100

16 laid upon the shoe. The outsole is preferably channeled as usual, a channel flap 18 being thus provided. The operation of stitching the outsole to the welt is next performed, an outsole seam 20 being thus made which secures the margin of the outsole and the welt 8 together.

In order that the welt 8 and the margin of the outsole may be held tight against the 10 upper to form a close edge, the last is now removed and a seam 22 formed, as shown in Fig. 3, through a marginal portion of the insole, the upper, the welt, and the channeled margin of the outsole. Preferably, though 15 not necessarily, a seam 22 is sewn at each side of the shoe and the insole may, as shown in Fig. 3, be split or channeled at each side of its marginal portion to provide lips 24 under which the last-mentioned seams may be hidden. Preferably too the seam 22 will be made 20 by a lockstitch machine with comparatively fine thread and its use will be confined to the shank portion of the shoe. This seam serves very effectively to prevent the welt 25 from separating from the upper and insures that the desired close shank appearance will be maintained throughout the life of the shoe. The channel flaps 18 and 24 are cemented and laid down, as shown at the right of Fig. 3, 30 the flap 18 covering the seams 20 and 22, and the flap 24 covering the seam 22 on the inside of the shoe.

In McKay sewed shoes, where no welt is present, the seam 22 will, of course, pierce the 35 margins of the insole, upper and outsole and hold the outsole close to the upper.

Having thus described my invention, what I claim as new and desire to secure by Letters Patent of the United States is:

40 1. A shoe comprising an insole, an upper and an outsole, a line of fastenings securing the upper and insole together but not entering the outsole, a second line of fastenings securing the outsole to the shoe, and a third 45 line of fastenings located adjacent to edges of contiguous margins of the insole and outsole and securing the insole, outsole and upper together.

2. A welt shoe having the welt secured to 50 the upper by one line of fastenings, having the welt secured to the outsole by another line of fastenings, and having adjacent margins of the welt, upper and outsole further secured together by a line of fastenings placed 55 outside of and supplemental to the said first-named lines of fastenings.

3. A shoe comprising an insole, upper, welt and outsole, the welt being attached to the upper and insole, on the one hand, and to the 60 outsole, on the other, and a line of stitching passing through the shank portion of the upper and through the extreme outer margins of the insole, welt and outsole.

4. A welt shoe having seams respectively 65 securing together the welt, upper and insole

and the welt and outsole, adjacent margins of the welt, upper, insole and outsole being further secured together by a line of through-and-through stitches placed outside of and supplemental to the said first-named seams.

5. That step in the manufacture of shoes having an upper, an insole and an outsole attached together in any usual and suitable manner, which consists in sewing together the outsole, the upper and the insole at the shank only by a through-and-through seam located outside of the other attaching means for said parts to hold the margin of the shank portion of the sole in close relation to the upper.

6. That improvement in methods of making shoes which consists in lasting an upper over upon an insole, applying an outsole, sewing together the insole, upper and outsole, and then inserting a line of fastenings through the outer margins of the insole and outsole and through the upper to form a close edge, said line of fastenings being located outwardly beyond the sewing by which the insole, upper and outsole are attached together.

7. That improvement in methods of making welt shoes having close shanks which consists in attaching together an insole, a welt, an upper and an outsole in any usual and suitable manner, and then sewing together by a through-and-through seam the margins of the insole, the welt, the upper and the outsole to form a close shank, said seam being located outwardly beyond the other means for attaching the insole, welt, upper and outsole together.

8. That method of producing close edge welt shoes having an inseam and an outsole-attaching seam which is characterized by inserting a line of fastenings through the outsole, the welt, the upper and the insole, said seam being located outwardly beyond the inseam and the outsole-attaching seam.

9. That method of producing close edge shoes which consists in providing an upper end an insole, providing an outsole with a channel in its outer margin, sewing together the provided parts to make a shoe, then sewing a through-and-through seam from the channel through the outsole, the upper and the insole, said seam being located outwardly beyond the first sewing of said shoe parts and near the outer edge of the insole, and cementing down the channel flap to cover the seam.

10. That method of producing close edge welt shoes which consists in providing an insole with a channel in the margin of its inner face, providing an outsole with a channel in the margin of its outer face, attaching by an inseam the welt to the upper and insole, attaching by a seam the welt to the outsole, then sewing a lockstitch seam from the channel to channel through the outsole, the welt, the upper and the insole at each side

of the shank, said seam being located outwardly beyond the inseam and the outsole-attaching seam, and cementing down the channel flaps to cover the seams.

5 In testimony whereof I have signed my name to this specification.

JOHN K. SMITH.
